No. 657,544.

Patented Sept. 11, 1900.

C. JAEGER.
EASEL ALBUM.

(Application filed Feb. 23, 1900.)

(No Model.)

Witnesses:

K. M. Gilligan.

Inventor
Christian Jaeger
D. S. Augustus B. Stoughton
Attorney

UNITED STATES PATENT OFFICE.

CHRISTIAN JAEGER, OF PHILADELPHIA, PENNSYLVANIA.

EASEL-ALBUM.

SPECIFICATION forming part of Letters Patent No. 657,544, dated September 11, 1900.

Application filed February 23, 1900. Serial No. 6,187. (No model.)

To all whom it may concern:

Be it known that I, CHRISTIAN JAEGER, a citizen of the United States, residing at Philadelphia, in the county of Philadelphia and 5 State of Pennsylvania, have invented certain new and useful Improvements in Albums, of which the following is a specification.

The object of the invention is to provide a combined album and easel or stand which 10 shall present a neat and attractive appearance and which may be readily taken apart for transportation, shipped in a compact form, and readily reassembled for use.

To these and other ends the invention comprises the improvements hereinafter described and claimed.

The nature, characteristic features, and scope of the invention will be more fully understood from the following description, taken 20 in connection with the accompanying drawings, forming part hereof, and in which—

Figure 1 is a perspective view of an album and easel or stand embodying features of my invention. Fig. 2 is an illustrative view showing the album and parts of the easel or stand about to be assembled. Fig. 3 is a broken section showing a detail of construction. Fig. 4 is a detail view of one of the hinges, and Fig. 5 shows a slight modification of my in- 30 vention.

In the accompanying drawings, a and a' are legs forming part of a detachable easel or stand and cut away, as at a² and a³, to accommodate a photograph - album or the like b, which may be hinged, as at a⁴ and a⁵. Detachably holding the legs together is a back or brace portion c, which may constitute a receptacle for photographs and the like and which may be provided with a lid. Forming 40 part of or secured to the legs a and a' are guide pieces or ways d, adapted to receive the flanges of strips d', attached to the portion c, and to limit the movement of the strips by the solid portion d².

In transportation the various parts of the album and easel or stand are packed in a suitable receptacle and are received by the purchaser in a detached condition, thus insuring their receipt in perfect condition.

To assemble the different parts, all that it is necessary to do is to take the legs a and a' and fit or slide the parts d and d' together until the part d comes into contact with the portion d², thus forming a rigid easel or stand 55 for the reception of the album. The album, which is provided with sections of hinges and pintles e, is shifted until the pintles are slipped into a hinge-section e', attached to the easel or stand and adapted to receive the same, whereupon fastening devices, as pins e², may be inserted to prevent accidental detachment of the hinge members. It will thus be apparent that the operation of assembling these parts is quite simple and that they may be at any time readily taken apart.

In use when the album has become filled the more antiquated photographs may be taken out and placed in the receptacle c, thus making room in the album for photographs of a more recent type.

Instead of hinging the album to the portions cut away in the easel or stand, as shown in Figs. 1 and 2, it may be hinged to the upper portion of the same, as is illustrated in Fig. 5, thus preventing any riding up of the 75 back cover of the album, which might occur in turning over the leaves.

It will be obvious to those skilled in the art to which the invention appertains that modifications may be made in detail without departing from the spirit thereof. Hence I do not limit myself to the precise construction and arrangement of parts hereinabove set forth and illustrated in the drawings; but,

Having thus described the nature and objects of the invention, what I claim as new, and desire to secure by Letters Patent, is—

1. In combination a portable easel or stand comprising legs constructed to receive an album, a back portion which is adapted to support the legs, flanged members and their complemental fixed ways interposed between the back portion and legs, and detachable hinges interposed between the stand and album, substantially as described.

2. In combination an album, a portable stand comprising legs cut away to receive the album, guide pieces or ways on the legs, a back portion, strips mounted on the back portion and adapted to track in said ways, and 100 detachable hinges interposed between the stand and album, substantially as and for the purposes set forth.

In testimony whereof I have hereunto signed my name.

CHRISTIAN JAEGER.

In presence of—

W. J. JACKSON,

K. M. GILLIGAN.